UNITED STATES PATENT OFFICE.

THOMAS H. MARTEN, OF NEW YORK, N. Y., ASSIGNOR TO MARTEN FREEMAN COMPANY LIMITED, OF TORONTO, ONTARIO, CANADA, A CORPORATION.

SHIP'S DAVIT.

1,245,752.

Specification of Letters Patent.

Patented Nov. 6, 1917.

Application filed January 2, 1917. Serial No. 140,244.

To all whom it may concern:

Be it known that I, THOMAS HENRY MARTEN, a subject of the King of Great Britain, and resident of the city and State of New York, one of the United States of America, have invented certain new and useful Improvements in Ships' Davits, as described in the following specification and illustrated in the accompanying drawings, 5 that form part of the same.

This invention relates to improvements in ships' davits and particularly to that form of davit in which the boom swings in a vertical plane and is pivotally connected intermediate of its length to a movable member by means of which the swinging movement is controlled.

One of the main objects of the invention is to minimize the longitudinal stress upon the 20 means for swinging the boom, thereby reducing the labor of operating the boom.

A further object is to overcome the difficulties met with in taking up the slack and stretch in the falls and in clearing the boat 25 from the chocks and in moving the boat outboard and inboard to clear the side of the ship's deck.

Still further objects are to simplify the construction and to obtain the maximum 30 rigidity and stability of the davit.

In the accompanying drawings, Figure 1 is a side elevational view of my improved davit showing the location of the parts in the extreme inboard and outboard positions.

35 Figs. 2 and 3 are small diagrammatic views illustrating the difference in the path of movement of the boom head between a machine having a horizontal path of movement for the intermediate pivot of the boom and one having an inclined path of movement.

Fig. 4 is an enlarged longitudinal vertical sectional view through the bearing end of the boom operating spindle and through the 45 means for swinging the davit.

Fig. 5 is a vertical transverse section through the boom on the center line of its pivotal connection, the section being broken and showing the connection of the lower end 50 of the boom.

Like numerals of reference indicate corresponding parts in each figure.

The principal feature of the invention consists in effecting a continuous upward movement of the intermediate pivotal point of

connection with the boom operating means coincident with the outward movement thereof to counteract the downward tendency of movement of the boom head due to its increasing angularity from the vertical. 60

In the application of the invention herein shown the frame 1 is preferably formed of cast-metal and is substantially a unitary structure of T shape section to give rigidity and strength. The end brackets 2 and 3 65 may or may not be formed integral with the frame and these are joined across the top by the top bar 4 which is also of a T-shaped section.

The upper side 5 of the main portion of 70 the frame is of substantially T shape in cross section and the top surface thereof is arranged with an outward and upward incline and forms a trackway upon which a suitable carriage is adapted to travel. 75

The carriage 6 here shown is formed with a pair of side flanges 7 adapted to overhang and engage the side edges 8 of the rail top 5 and is supported upon rollers 9 which travel upon said rail top, being journaled 80 upon pins 10 extending between said side flanges. The carriage is operated to move longitudinally upon the trackway 5 by means of a screw spindle 11 which is journaled at the outer end in a bracket 3 and at the inner 85 end in a bearing 12 in the bracket 2.

The bearing 12 is here shown formed of a Babbitt and ball thrust type though any desirable form of bearing may be adopted. The screw spindle 11 operates in a nut 13 90 held between the end lugs 14 of the carriage 6.

15 is a pivot pin secured in the carriage 6 midway between the rollers 9 and extending beyond the sides of said carriage. 95

16 is the boom which is here shown of the bifurcated type, though a solid type may be used if desired. The boom is pivotally connected intermediate of its length to the pivot pin 15, the lower end being here shown as 100 being held by the pivotal link 17 but may be otherwise suitably connected or supported so as to insure its proper function in supporting the load in the outward travel of the boom head. 105

The boom is shown in Fig. 1 of the drawings in its position of rest, sloping inboard from the vertical and it will be readily seen that upon the rotation of the screw spindle the carriage moves upwardly as well as out- 110

wardly upon the inclined track 5, in addition to the rise of the head due to the pivotal movement of the boom to the vertical position, consequently carrying the boom 5 head farther in an upward direction and thereby insuring the taking up of the slack and stretch in the falls and lifting the boat clear of the chocks.

As the outward movement of the boom is 10 continued it swings upon its intermediate pivot and through the swinging movement the tendency of the boom head is to operate in an outward downward curve. This tendency is counteracted by the upward travel of 15 the pivot with the result that the boom head and consequently the load operates in a path nearer to the horizontal and therefore less power is required to control the load than would be the case if the boom 20 head moves in a more downwardly inclined path. This also insures the load being carried outboard to clear the side rail of the deck of the ship, thus obviating the dangers of fouling in the launching operation.

25 The ultimate result of this arrangement is that there is less drop and raise to the load as the boom is swung outboard and inboard, thus minimizing the strain on the pivotal moving means and therefore reducing 30 the necessary power for swinging the davit.

The simple construction herein set forth obviates the necessity of complicated gearing in the davit and also simplifies the arrangement of the falls and insures a safe and easily operated device.

My invention is herein shown as applied to a davit in which the boom is connected at its lower end to a swinging link but it must 40 be understood that the invention may be applied to other forms of davits if desired.

What I claim as my invention is:—

1. In a ship's davit, a frame, a boom supported from said frame and adapted to 45 swing in a vertical plane, means pivotally connected to said boom intermediate of its length for controlling the swinging movement thereof, and means for effecting a continuous upward movement of the point of

connection between the boom and the boom 50 controlling means coincident with the outward movement thereof to counteract the downward tendency of the movement of the boom head due to its increasing angularity from the vertical. 55

2. In a ship's davit, a frame, a boom supported from said frame and adapted to swing in a vertical plane, means pivotally connected to said boom intermediate of its length for controlling the swinging movement thereof, and means for guiding the point of pivotal connection of the boom and boom controlling means upwardly and outwardly in a straight inclined plane.

3. In a ship's davit, a frame having a 65 rigid trackway inclined upwardly and outwardly in a straight line, a boom supported from said frame and adapted to swing in a vertical plane, a member pivotally connected to said boom intermediate of its 70 length and adapted to travel on the inclined trackway of said frame, and means operatively connected with said pivotally connected member adapted to effect the swinging 75 of the boom.

4. In a ship's davit, a frame having a rigid trackway inclined upwardly and outwardly, a boom supported from said frame and adapted to swing in a vertical plane, a member pivotally connected to said boom 80 intermediate of its length and adapted to travel on the inclined trackway of said frame, and a screw spindle journaled in said frame and engaging said pivotally connected member and adapted to move said member upon said trackway to effect the swinging 85 of the boom. 95

5. In a ship's davit, a frame having a rigid trackway inclined upwardly and outwardly, a carriage mounted on said trackway having a rolling contact therewith and depending flanges adapted to engage the sides of said trackway, a boom pivotally connected intermediate of its length to said carriage, and means for operating said carriage on 90 said trackway. 95

THOMAS H. MARTEN.
